(57) **CLAIM**

We claim the ornamental design for a microscope viewing head, as shown and described.

DESCRIPTION

FIG. 1 is a rear perspective view of a microscope viewing head.

FIG. 2 is a left side elevational view thereof.

FIG. 3 is a right side elevational view thereof.

FIG. 4 is a rear elevational view thereof.

FIG. 5 is a front elevational view thereof; and,

FIG. 6 is a top plan view thereof.

The bottom side of the microscope viewing head forms no part of the claimed design.
